2,562,164

METHOD OF TRANSFERRING FLUIDS

Edgar L. Hinkson, Detroit, Mich., assignor to The General Detroit Corporation, Detroit, Mich., a corporation of Michigan

Application June 26, 1946, Serial No. 679,389

5 Claims. (Cl. 62—170)

1

The present invention relates to the art of transferring fluids under pressure from one container to another, particularly in connection with the handling of fluids which are stored in the compressed, liquid state, but which vaporize at ordinary temperatures and pressures. While the invention is particularly applicable to charging fire extinguishers with liquid carbon dioxide, such use will be recognized as representative rather than exclusive.

An important object of the invention is to provide means whereby a greater quantity of a compressed fluid may be induced to flow into a receptacle to be charged than it has heretofore been possible to introduce without the use of a charging pump. In charging fire extinguisher flasks from a source of liquid carbon dioxide under high pressure, it has heretofore been common to apply a transfer pump, since when the source is directly connected to the flask, the pressure developed in the latter as the liquid level rises therein prevents adequate filling. For example, in filling such a flask which is designed to accommodate 15 pounds of carbon dioxide, if the flask is connected to a supply source having a pressure of approximately 900 pounds per square inch at a temperature in the neighborhood of 70° F., only about 11 pounds of CO₂ will enter the flask before the transfer ceases due to equalization of pressures at the prevailing temperatures. When the method of the present invention is practiced, however, it is possible, under the same conditions, without the use of a pump or other supplemental pressure generating apparatus, and in a quick, simple and convenient manner, to place a full charge of 15 pounds in such a flask from a source at the indicated pressure. Equivalent results are attainable with other proportions and pressures.

Other objects and advantages will be apparent upon consideration of the present disclosure in its entirety.

In the drawings,

Figs. 1 and 2 are front and side elevational views respectively of a flask-supporting stand of the so-called A frame type, showing a flask mounted thereon in one position which it occupies during the filling thereof in accordance with the method of the present invention, also showing the arrangement of suitable conduit and valving means; and

Fig. 3 is a view similar to Fig. 1 showing the flask inverted.

The principal elements of suitable apparatus for carrying out the present invention are shown in the drawings. The source (not shown) of CO₂

2

or other fluid under pressure is connected to the flask 10 by means including a tube or hose 12 of sufficient length and flexibility to permit inverting the flask without disconnecting the tube. The flask is shown as a fire extinguisher body of the type and size designed to accommodate 15 pounds of CO₂. Flasks of the indicated variety have a volumetric capacity in the neighborhood of 612-622 cubic inches, and are equipped with a valve 14 having a coupling nipple 16 through which the fluid is discharged during operation of the fire extinguisher, and to which the filler hose 12 is adapted to be connected in the manner indicated. Valve 14 is left open during all of the steps of the charging operation herein described and until the flask is full and ready for final sealing.

For convenience, the flask to be charged is preferably secured, as by means of the grappling chain 18, to the rotatable top cross bar 20 of an A-frame support 22, this arrangement being such that the flask may readily be inverted, to be supported either in the upright position in which it is shown in Figs. 1 and 2 of the drawings, or in the inverted position shown in Fig. 3, being stable in either position. The hose 12 is coupled at 13 to the supply pipe 25, a shut-off valve 24 being incorporated in the supply pipe, which is also provided with a manually operable vent valve 26 interposed between the shut-off valve and the coupling 13.

In carrying out the method of the invention, a small quantity (3 pounds is adequate in the case of a 15 pound flask) of liquid CO₂ is admitted to the flask and the supply is then shut off at the valve 24. The flask is then inverted, to the position shown in Fig. 3, and vent valve 26 is opened, permitting the cooling charge to escape in gaseous form to the atmosphere. The flask is internally provided with a discharge "siphon" tube 28 extending from the valve 14 to a point near the bottom of the flask, so that with the flask in the inverted position shown in Fig. 3 the expanding refrigerating charge must escape through the then uppermost bottom portion of the flask and the arrangement is such that the gases sweep across and vaporize in intimate contact therewith although evaporation occurs within substantially all portions of the flask, which is rapidly cooled to a low temperature by such vaporization. When CO₂ is utilized in the indicated manner, all of the three pound refrigerating charge escapes in gaseous form with the exception of approximately six ounces, which is solidified. It is not necessary to await the vaporization of such solidified portion, and valve 26 is

closed when all but this has escaped. The flask is then returned to the upright position and valve 24 reopened. The temperature of the flask has been so reduced, in the manner above indicated, that the entering charge is chilled by the flask, and the pressure within the flask is resultantly maintained at such a relatively low level that a full charge of 15 pounds of CO₂ at room temperature will readily enter the flask from a source at a pressure of 900 pounds per square inch.

If too long an interval is allowed to elapse between the refrigeration of the flask and the opening of valve 24 to admit the charge, so that the flask has partially warmed up, a pressure balance may occur too soon, so that the inflow ceases somewhat short of a full charge, due to the tendency of the entering charge to warm the upper portions of the upright flask. If this occurs under conditions such that only a relatively small percentage of the charge refuses to enter the flask, as for example after 13 or 14 pounds have entered a 15 pound flask, the required additional charge may be induced to enter by again promptly inverting the flask to the position shown in Fig. 3, with the valve 24 still open. This carries the chilled liquid into contact with the head portions of the flask and promotes uniform cooling of the flask, counteracting the warming of the head portion which has resulted from the previous inflow with the flask in the upright position. If the interval previously referred to was not too great, such uniform cooling further or again reduces the internal pressure, and an additional quantity of fluid is thereby induced to enter the flask, being introduced thereto through the siphon tube 26 and above the liquid level. A full charge may in this manner be introduced with the flask at a somewhat higher average temperature. The flask of course then be sealed at the valve 14 in the usual manner.

It will be apparent that variations may be introduced without departing from the spirit and scope of the subjoined claims.

I claim:

1. The process of charging, with a fluid of the class which is adapted to be stored in the liquid state under pressure but which vaporizes at ordinary temperatures and pressures, a receptacle of the variety having a head having an opening formed therein adapted to serve as an inlet through which the receptacle may be charged and a siphon tube connected to said opening and extending to a remote part of the receptacle, comprising connecting the receptacle to a high pressure source for a limited period of time to introduce into the receptacle a relatively small quantity of such fluid with the receptacle in one position, interrupting the connection between the receptacle and such source, inverting the receptacle, venting the fluid from the receptacle with the receptacle in the inverted position to refrigerate the receptacle by expansion of the escaping fluid, and re-establishing connection between the receptacle and said high pressure source to permit the fluid to flow from the source into the chilled receptacle.

2. The process of charging, with a fluid of the class which is adapted to be stored in the liquid state under pressure but which vaporizes at ordinary temperatures and pressures, a receptacle of the variety having a head having an opening formed therein adapted to serve as an inlet through which the receptacle may be charged and a siphon tube connected to said opening and extending to a remote part of the receptacle, com-

rising connecting the receptacle to a high pressure source for a limited period of time to introduce into the receptacle a relatively small quantity of such fluid with the receptacle in a position in which the head is elevated and the siphon tube extends downwardly therefrom, interrupting the connection between the receptacle and such source, venting the fluid from the receptacle with the receptacle in a position in which the head is lowered and the siphon tube extends upwardly therefrom to refrigerate the receptacle by expansion of the escaping fluid, and re-establishing connection between the receptacle and said high pressure source to permit the fluid to flow from the source into the chilled receptacle.

3. The process of charging, with a fluid of the class which is adapted to be stored in the liquid state under pressure but which vaporizes at ordinary temperatures and pressures, a receptacle of the variety having a head having an opening formed therein adapted to serve as an inlet through which the receptacle may be charged and a siphon tube connected to said opening and extending to a remote part of the receptacle, com-

25 prising connecting the receptacle to a high pressure source for a limited period of time to introduce into the receptacle a relatively small quantity of such fluid, interrupting the connection between the receptacle and such source,
30 venting the fluid from the receptacle with the receptacle in a position in which the head is lowered and the siphon tube extends upwardly therefrom to refrigerate the receptacle by expansion

35 of the escaping fluid, and re-establishing connection between the receptacle and said high pressure source to permit the fluid to flow from the source into the chilled receptacle with the chilled receptacle disposed with the head elevated, allowing such inflow to continue after reconnection.

40 of the receptacle to the source until a substantial balance is reached at the prevailing conditions of temperature and pressure, the fluid from the source being at a higher temperature than the chilled receptacle, whereby the fluid tends to warm the receptacle nonuniformly during inflow. 45 45 therein to due to the fact that heat is first absorbed from the fluid in the vicinity of the opening and head, and thereafter again turning the receptacle to a position in which the head is depressed to permit more extended contact between the fluid and the receptacle and thereby promote more uniform heat absorption from the fluid by a greater proportion of the mass of the receptacle, whereby the pressure prevailing within the receptacle is reduced to permit additional fluid inflow. 50 55

4. The process of charging with an expansible fluid from high pressure source a receptacle of the variety having an opening adapted to serve as an inlet through which it may be charged, 60 which comprises precooling the receptacle, connecting the receptacle to the source so that the fluid may flow from the source into the receptacle through said opening while the latter is disposed in a position in which the inlet opening is near 65 the top, the fluid flowing through said opening until a substantial balance is reached at the prevailing conditions of temperature and pressure, the fluid from the source being at a higher temperature than the precooled receptacle, whereby 70 the fluid tends to warm the receptacle during its inflow thereinto and whereby such heating of the receptacle occurs non-uniformly, due to the fact that heat is first absorbed from the fluid in the vicinity of the inlet, while the fluid thus cooled 75 flows to and remains longer in contact with other

parts of the receptacle remote from the inlet, inverting the position of the receptacle to induce flow of the fluid into contact with a greater area of the interior of the receptacle, whereby heat absorption from the fluid occurs over a large portion of the internal surface area of the receptacle and the pressure prevailing within the receptacle is thereby reduced, and thereafter, and before the receptacle again warms up beyond a desired temperature permitting the fluid to flow from the source into the portion of the receptacle within which the pressure has been so reduced.

5. The process of charging, with a fluid of the class which is adapted to be stored in the liquid state under pressure but which vaporizes at ordinary temperatures and pressures, a receptacle of the variety having a head having an opening formed therein adapted to serve as an inlet through which the receptacle may be charged and a siphon tube connected to said opening and extending to a remote part of the receptacle, comprising connecting the receptacle to a high pressure source for a limited period of time to introduce into the receptacle a relatively small quantity of such fluid with the receptacle in a position in which the head is elevated and the siphon tube extends downwardly therefrom, interrupting the connection between the receptacle and such source, venting the fluid from the receptacle with the receptacle in a position in which the head is lowered and the siphon tube extends upwardly therefrom to refrigerate the receptacle by expansion of the escaping fluid, and re-establishing connection between the receptacle and said high pressure source to permit the fluid to flow from the source into the chilled receptacle with the

chilled receptacle disposed with the head elevated, allowing such inflow to continue after reconnection of the receptacle to the source until a substantial balance is reached at the prevailing conditions of temperature and pressure, the fluid from the source being at a higher temperature than the chilled receptacle, whereby the fluid tends to warm the receptacle non-uniformly during inflow thereinto due to the fact that heat is first absorbed from the fluid in the vicinity of the opening and head, and thereafter again turning the receptacle to a position in which the head is depressed to permit more extended contact between the fluid and the receptacle and thereby promote more uniform heat absorption from the fluid by a greater proportion of the mass of the receptacle, whereby the pressure prevailing within the receptacle is reduced to permit additional fluid inflow.
